UNITED STATES PATENT OFFICE.

JOHN MASON SIVADIE, OF OROFINO, IDAHO.

SOIL-PULVERIZER.

No. 897,310.

Specification of Letters Patent.

Patented Sept. 1, 1908

Application filed October 8, 1907. Serial No. 396,498.

To all whom it may concern:

Be it known that I, JOHN MASON SIVADIE, a citizen of the United States, residing at Orofino, in the county of Nez Perce and 5 State of Idaho, have invented a new and useful Soil-Pulverizer, of which the following is a specification.

This invention has relation to soil pulverizers and it consists in the novel construction 10 and arrangement of its parts as hereinafter shown and described.

The object of the invention is to provide a 15 pulverizer as indicated which consists of a frame having pivotally mounted therein a series of soil-engaging members and means for swinging the same simultaneously to adjust the angle with relation to the ground. The said pivoted members are of special 20 construction and are especially adapted for the character of work to be performed.

In the accompanying drawing:—Figure 1 is a top plan view of the pulverizer. Fig. 2 is a transverse sectional view of the pivoted member thereof. Fig. 3 is a perspective 25 view of an end piece for said member. Fig. 4 is a sectional view of an end portion of said member showing the end piece inserted therein. Fig. 5 is a side elevation of a lever mechanism used upon the pulverizer.

30 The implement consists of the substantially rectangular frame 1 which is provided at its rear side with parallel bars 2 preferably made from channel iron, while the forward portion of the frame 1 is preferably formed up of angle iron. The soil-engaging members 3 are pivoted at their ends in the sides of the frame 1, the said frame being provided with perforations or bearings for the reception of the pivots or trunnions of the members 3. An arm 4 is mounted upon the forward edge of each member 3 and the rod 5 is pivotally attached to the arms 4. The link 6 is pivoted at its forward end to the rear end of the rod 5 and at its rear end to 45 the lever 7 which is fulcrumed to the strip of angle iron 8 which in turn is secured at its end portions to the bars 2, 2 of the frame 1. The gear segment 9 is attached at its ends to the strip 8 and is adapted to be engaged by 50 the pawl 10 mounted upon the lever 7. Through the instrumentality of the lever 7

the link 6 and the rod 5, the members 3 may be turned axially in the frame 1 and when in proper position are held in such position by the pawl 10 which engages the 55 teeth of the segment 9.

The members 3 are made of sheet metal which is formed substantially U-shaped in transverse section with the strip of channel iron 11 connecting the ends of the U-shaped portion together. Each member 3 is formed as a hollow body with the strip 11 closing one edge thereof and the strips 12 inserted in the ends thereof. The strips 12 are provided upon their outer sides with the trunnions 13 60 at the bases of which are the inclined guides or guards 14. The said guides 14 are wedge-shaped in transverse section and are adapted to prevent the ends of the members 3 from coming in contact with the inner surfaces of 65 the sides of the frame 1, at the same time, the said guides by reason of their peculiar configuration will not permit the accumulation of mud or dirt between the ends of the pivoted members and the sides of the frame to 70 such an extent as to materially interfere with the ready shifting of the said pivoted members.

Having described my invention what I 75 claim as new and desire to secure by Letters- 80 Patent is:—

1. An implement as described comprising a frame, members pivoted at their ends to the sides of said frames and having at the bases of their pivots inclined guides which are 85 wedge-shaped in cross-section.

2. An implement as described comprising a frame, a member pivotally mounted therein and having a body portion formed up of sheet metal substantially U-shaped, a strip of 90 channel iron connecting the ends of the U-shaped portions together, strips inserted in the ends of the pivoted member and having trunnions which engage the frame.

In testimony that I claim the foregoing as 95 my own, I have hereto affixed my signature in the presence of two witnesses.

JOHN MASON SIVADIE.
